UNITED STATES PATENT OFFICE.

BRITTON POULSON, OF FORT WAYNE, INDIANA, ASSIGNOR OF ONE-HALF
TO WILLIAM D. SCHIEFER, OF SAME PLACE.

DEVICE FOR DETACHING BUTTONS.

SPECIFICATION forming part of Letters Patent No. 367,319, dated July 26, 1887.

Application filed February 12, 1887. Serial No. 227,390. (No model.)

To all whom it may concern:

Be it known that I, BRITTON POULSON, of Fort Wayne, county of Allen, and State of Indiana, have invented a new and useful Improvement in Button-Detaching Devices, of which the following is a full, clear, and exact description, reference being had to the accompanying drawings, making part of this specification.

10 My invention relates to a device for removing buttons from shoes and analogous purposes; and it consists in a novel construction of case having converging blades or cutters for severing the button-fastenings and a spring or springs for holding the button in proper relation to the cutters, said case being adapted to receive and hold the buttons removed, and having a removable cap or cover facilitating the removal of the buttons from the case, as 20 hereinafter described and claimed.

In the accompanying drawings, Figure I is a front elevation of my improved device. Fig. II represents a section through the device, taken in line with the intersection of the 25 converging blades or cutters; and Fig. III is a horizontal section through one side of the lower end of the case, showing the manner of applying or attaching the cutter to the case.

A represents a hollow cylindrical case, made 30 of any suitable material, preferably of metal, closed at one end and open at the other, as shown. Upon said open end a cap, A', is screwed or adapted to be placed and fastened in any suitable manner. Near the opposite 35 end of this cylinder or case there is a slot, as shown, and upon either side of this slot are flanges a a, substantially of wedge shape, tapering toward the closed end of the casing A, and provided at or near their upper edges 40 each with a groove, a', on their inner adjacent faces, for the reception of the cutter-plate B, which is adapted to slide therein and be retained. The cutter B is formed of a steel plate provided with a V-shaped slot, (shown 45 at B', Fig. I,) the adjacent edges of which are sharpened or have a knife-edge, which will cut the thread which secures the button to the shoe.

C represent two flat springs located on

either side of the center of the slot B', and 50 secured by screws c c or otherwise to the flanges a a or shoulders formed upon said flanges, as preferred. These springs diverge from the cutter inwardly, and their purpose is to hold the head of the shoe-button under 55 them and to draw the button away from the shoe-flap, so that the knife may act on the securing-thread, and not on the shank of the button. The cylindrical casing A is further depressed, as shown at a', for allowing room 60 for the head of the button to pass beneath the springs C C and into the hollow casing.

In operation the device is grasped by the hand and so placed relatively to the shoe from which the button is to be removed that the button will enter the slot in the casing A, the head of the button traveling beneath the springs C C and the shank between the same. As the device is advanced or moved along by the operator, the head of the button slides beneath 70 the springs, and is thus forced or drawn away from the shoe to which it is sewed, and as it continues to approach the end of the V-shaped cutter the converging blades or edges thereof act upon the threads or strands which secure 75 the button to the shoe and sever the same, the springs C serving to withdraw the shank of the button far enough away to prevent any liability of the cutter being injured by contact with the same. As soon as severed from 80 the shoe the button drops into the cylindrical casing, and is there retained until a number have collected, when by removing the cap A' the buttons may be removed therefrom.

Having thus described my invention, what 85 I claim as new, and desire to secure by Letters Patent, is—

1. In a device for removing buttons, the combination, with the case or hollow cylinder, of the converging blades or cutters, arranged substantially as described.

2. The combination, with the case or cylinder, of the converging blades or cutters and springs diverging inwardly therefrom, for the purpose and substantially as described.

3. In a device for removing buttons, the combination, with the hollow case A, provided with the cap A', of the converging cut-

ters B, arranged and adapted to operate substantially as described.

4. In a device for removing buttons, the combination, with the case having the removable cap, of the converging cutters and the springs diverging inwardly from the cutters, all substantially as described.

In testimony whereof I have hereinunto set my hand this 8th day of February, A. D. 1887.

BRITTON POULSON.
